HAIR GEL DISPENSING COMB

Gladys M. Guinette, Sandy, Oreg.
(7631 SE. 190th Drive, Portland, Oreg. 97236)

Filed Nov. 15, 1974, Ser. No. 523,972

Term of patent 14 years

Int. Cl. D28—03

U.S. Cl. D86—8

FIG. 1 is a side elevational view of a hair gel dispensing comb showing my new design,

FIG. 2 is a bottom plan view thereof,

FIG. 3 is a top plan view thereof,

FIG. 4 is a left end elevational view thereof, and

FIG. 5 is a right end elevational view thereof.

I claim:

The ornamental design for a hair gel dispensing comb, as shown.
